UNITED STATES PATENT OFFICE.

FREDERICK SHICKLE, OF ST. LOUIS, MISSOURI.

PIPE-MOLDING MACHINE.

SPECIFICATION forming part of Letters Patent No. 289,036, dated November 27, 1883.

Application filed July 27, 1883. (No model.)

To all whom it may concern:

Be it known that I, FREDERICK SHICKLE, of St. Louis, Missouri, have made a new and useful Improvement in Pipe-Molding Apparatuses, of which the following is a full, clear, and exact description, reference being had to the annexed drawings, making part of this specification, in which—

Figure 1 is a view in perspective, showing 10 a flask-bottom having the improvement; Fig. 2, a vertical section; Fig. 3, a vertical section upon an enlarged scale, showing a portion of the flask-bottom before the coating is applied to the socket; Fig. 4, a vertical section, showing 15 the coating formed upon the socket; and Fig. 5, a section similar to that of Fig. 4, but in a different plane.

The same letters denote the same parts.

In a pending application for Letters Patent 20 I have described an improvement in pipe-molding apparatus for forming the bell of the pipe, and consisting in the mode of constructing the socket which receives the lower end of the core-bar.

25 This improvement relates to the means employed in molding the coating upon the core-bar socket.

A represents the flask-bottom, having the socket B and socket-coating C, as in the construction referred to.

30 The coating C is formed upon the socket B, as follows: A boxing, D, preferably in three parts, $d d d$, is placed around the socket and centered by means of a ring, E, which is dropped between the lugs $a a$ of the flask-bottom and the boxing, or, rather, the lugs $d' d'$ of the boxing. The boxing rests upon slight elevations $a' a'$ upon the flask-bottom. These seats $a' a'$, however, are not wide enough to 35 practically interfere with the application of the coating material to the flask-bottom at c. The several parts $d d d$ of the boxing are suitably united, as by the bolts and keys $d' d'$. A

ring, F, is placed in the socket B. The coating C is then molded upon the socket between 45 the boxing D and ring F, and in doing this the device H H' is inserted. This device is in practice inserted before the coating material is entirely filled into the boxing, and after its insertion, as shown, the coating is completed, so that the device H H', when the coating is completed, is entirely beneath the coating. 50 So far as this mode of forming a coating upon the socket is concerned, the device H H' may or may not be used. The ring F at f is shaped 55 so that when the core is ultimately placed in the socket there is a narrow annular space left between the core and the coating, the purpose of which is when the core is placed in the socket the lower end of the core is dropped slightly 60 below the top of the coating, for by causing the coating to lap the core slightly there is no liability of the pipe internally being too small in diameter. The metal, in casting, runs into the annular space left between the core and 65 coating, forming a thin annular fin, which, when the pipe is cast, can be readily removed therefrom.

I claim—

1. The combination of the boxing D, the 70 bottom A, and the ring E, as and for the purpose referred to.

2. The combination of the bottom A, the socket B, the boxing D, and the ring F, substantially as described.

3. The combination of the bottom A, the socket B, the boxing D, and the rings E F, substantially as described,

4. In combination with the socket B, the ring F, having the projection f, for the purpose described.

FREDERICK SHICKLE.
